FIG. 1 is a front elevational view of a light standard or similar article showing my new design.

FIG. 2 is an elevational view thereof at a viewing angle of 45° from that of FIG. 1.

FIG. 3 is an enlarged cross-sectional view taken on line 3—3 of FIG. 1.

FIG. 4 is an enlarged cross-sectional view taken on line 4—4 of FIG. 1.

FIG. 5 is a front elevational view of a second embodiment of my design.

FIG. 6 is an elevational view thereof at a viewing angle of 45° from that of FIG. 5.

FIG. 7 is an enlarged cross-sectional view taken on line 7—7 of FIG. 5.

FIG. 8 is an enlarged cross-sectional view taken on line 8—8 of FIG. 6.

FIG. 9 is a front elevational view of a third embodiment of my design.

FIG. 10 is an elevational view thereof at a viewing angle of 45° from that of FIG. 9.

FIG. 11 is an enlarged cross-sectional view taken on line 11—11 of FIG. 10.

FIG. 12 is an enlarged cross-sectional view taken on line 12—12 of FIG. 9.

FIG. 13 is an enlarged cross-sectional view of a fourth embodiment of my design, the cross section being taken on the embodiment on a plane identical to line 11—11 of FIG. 10, it being understood that this embodiment differs from FIG. 10 in cross section only.

FIG. 14 is another enlarged cross-sectional view of the fourth embodiment, this cross section being taken on a plane identical to line 12—12 of FIG. 9.

FIGS. 15—16 are front elevational views of additional embodiments of my design.

The lamps are shown in broken lines in FIGS. 1—2, 5—6, 9—10 and 15—16 for illustrative purposes only. The light standard is fragmentarily shown in FIGS. 15—16 for convenience of illustration.

This is a division of design application D. 19,635, filed October 20, 1969.

I claim:

The ornamental design for a light standard or similar article, as shown and described.
